PETER F. AUGENBRAUN, OF STAMFORD, CONNECTICUT, ASSIGNOR TO THE YALE & TOWNE MANUFACTURING COMPANY, OF STAMFORD, CONNECTICUT.

STRIKE OR KEEPER FOR RIM-LOCKS.

1,377,051.

Specification of Letters Patent.

Patented May 3, 1921.

Application filed October 20, 1920. Serial No. 418,183.

To all whom it may concern:

Be it known that I, PETER F. AUGENBRAUN, a citizen of the United States, and a resident of Stamford, in the county of Fairfield and State of Connecticut, have invented certain new and useful Improvements in Strikes or Keepers for Rim-Locks; and I do hereby declare the following to be a full, clear, and exact description of the invention, such as will enable others skilled in the art to which it appertains to make and use the same.

My invention relates to an improvement in strikes or keepers for rim locks, the object being to provide improved means for securing the strike against movement if the screws securing it to the door jamb should it become loose and also for lessening the possibility of its forcible removal by jimmying.

A further object is to provide means for taking the jars or stresses to which the strike is subjected by its frequent contact with the latch bolt, from the securing screws, thus preventing the strike from becoming loose.

With these and other objects in view, my invention consists in the details of construction as will be more fully explained and pointed out in the claims.

In the accompanying drawings; Figure 1 is a view of the strike secured to a door jamb; Fig. 2 is a view in perspective of the keeper removed; Fig. 3 is a similar view of the jamb prepared to receive the keeper; Fig. 4 is a view in section on the line 4—4 of Fig. 1 and Fig. 5 is a view in section on the line 5—5 of the same figure.

10 represents the door jamb mounted to receive the flange 11 of the strike or keeper 12. This strike or keeper overlaps the outer face of the door jamb and is provided with the flange 11 to overlap the side edge of the latter, the said flange being provided with 45 screw holes for the screws 13 which secure the strike to the jamb, and which of course are concealed when the door is closed.

The strike thus far described is substantially identical with rim lock strikes now in common use, the improvement consisting in 50 lugs 14 cast on the rear edge or face 15 of the strike, parallel with the flange 11 and adapted to enter holes 16 formed in the

front face of the jamb, so that when the strike is in place, it will be held by the 55 screws 13 and by the lugs 14 at right angles to the screws.

These lugs 14 are made comparatively heavy, and are preferably located adjacent each end of the bolt housing member of the 60 strike, as shown, and each lug 14 is provided centrally with a pointed spur 17, which are employed for locating the holes 16. These lugs have a close fit within the holes 16 and together with the screws 13, securely hold the strike in place against the possibility of any lost movement due to the screws working loose, and also operate to take part of the strains to which the strike is subjected by its frequent contact with the 70 bolt, from off the screws, and of course assist in preventing the forcible removal of the strike by jimmying or otherwise.

In order that the location of the holes 16 in the door jamb may be quickly and accurately located, the lugs terminate in pointed spurs 17, so that after the mortise has been cut for the front face or flange 11 of the strike, the latter can then be applied to the jamb and by a sharp blow or pressure 80 on the outer face of the strike, the spurs 17 will be driven into the wood and locate the centers for the holes 16 which are subsequently formed by an ordinary boring tool.

When the strike is secured to the jamb, 85 the lugs being at right angles to the securing screws take part of the strain from the latter and absolutely prevent the strike from working loose.

Having fully described my invention what 90 I claim as new and desire to secure by Letters-Patent, is:—

1. As a new article of manufacture, a lock strike having a flange for the securing screws and integral lugs at the rear face of 95 the front portion of the strike and adapted to enter holes in the jamb.

2. As a new article of manufacture, a lock strike having a flange for the securing screws and rigid cylindrical lugs at the two 100 ends of the keeper parallel with said flange and adapted to enter holes or pockets in the front face of the jamb.

3. As a new article of manufacture, a lock strike having integral lugs with pointed 105 ends, the said lugs adapted to enter

holes or pockets in the jamb, and means for securing the strike to the jamb.

4. As a new article of manufacture, a lock strike having a flange with screw holes therein and also provided with integral pointed lugs the latter being parallel with the flange.

In testimony whereof, I have signed this specification in the presence of two subscribing witnesses.

PETER F. AUGENBRAUN.
